CLAIM

We claim the ornamental design for a clothing care machine, as shown and described.

DESCRIPTION

FIG. 1 is a front perspective view of a clothing care machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along line 8-8 of FIG. 2;

FIG. 9 is a cross-sectional view taken along line 9-9 of FIG. 2; and,

FIG. 10 is a front perspective view of a clothing care machine in which a user's image and it's reflection in the door are provided in dot-dash broken lines to illustrate an example environment.

The short dash-dash broken lines showing portions of the clothing care machine in the figures form no part of the claimed design. The dot-dash broken lines showing the user's image and it's reflection in FIG. 10 depict environmental structure and form no part of the claimed design.
